UNITED STATES PATENT OFFICE.

GEORGE HENRY WHEARY, OF RACINE, WISCONSIN.

AUTOMATIC LOCKING MEANS FOR TRUNKS.

1,290,445.

Specification of Letters Patent. Patented Jan. 7, 1919.

Application filed August 8, 1914. Serial No. 855,748.

To all whom it may concern:

Be it known that I, GEORGE HENRY WHEARY, a citizen of the United States, and resident of Racine, in the county of Racine and State of Wisconsin, have invented new and useful Improvements in Automatic Locking Means for Trunks, of which the following is a description, reference being had to the accompanying drawings, which are a part of this specification.

This invention relates to improvements in automatic locking means for trunks more particularly adapted for trunks which are locked at a plurality of points,

In trunks of the better class a plurality of keyed locking devices is usually provided for locking the trunk cover to the body portion. The independent operation of these locking devices is not convenient and requires considerable time and is otherwise objectionable.

It is one of the objects of the present invention to overcome the before mentioned objectionable features and provide a trunk locking means which may be controlled by a keyed engagement with one of the locks.

A further object of the invention is to provide a trunk locking means in which the unlocking and outward movement of the hasp member of one of the locks will automatically unlock the hasp member of another lock.

A further object of the invention is to provide a trunk locking means which is of simple construction, is strong and durable and which is well adapted for the purpose described.

With the above and other objects in view, the invention consists of the improved trunk locking means and its parts and its combinations as set forth in the claims, and all equivalents thereof.

In the accompanying drawings in which the same reference characters indicate the same parts in all of the views:

Figure 1 is a front view of a trunk provided with the improved locking means;

Fig. 2 is a vertical sectional view of the trunk and an inner view of the locking means thereof;

Fig. 3 is a sectional detail view on a larger scale taken on line 3—4 of Fig. 2 with the parts in locked position;

Fig. 4 is a similar view taken on the same section line with the parts in unlocked position;

Fig. 5 is a detail view on a larger scale of the means for unlocking the keyless lock;

Fig. 6 is a modified form of locking means for use in connection with wardrobe trunks; and

Fig. 7 is a detail sectional view on a larger scale taken on line 7—7 of Fig. 6.

Referring to the drawings the numeral 8 indicates the trunk body and 9 the hinged cover thereof. The cover is locked in closed position by two hasp locks 10 and 11 of which the lock 10 is the keyed lock and the lock 11 is automatically controlled by the keyed lock. The lock 10 comprises the spring hasp member 12 hinged to the cover and the escutcheon member 13 secured to the body portion of the trunk. The hasp member is provided with the usual locking barrel 14 which enters the trunk through the barrel opening 15 of the escutcheon member 13 and the bolts 11 of said barrel member lock the two parts together in the ordinary manner. The hasp member is also provided with a spring 17 for yieldingly holding the said member in its outer open position.

A curved lever arm 18 pivoted at one end to the escutcheon plate 13 extends into the trunk and its opposite free end 18' is positioned to be engaged by the barrel 14 when the said barrel is moved to closed position. The purpose of this lever arm will be described later.

A key 19 controls the opening and closing of said lock.

The automatically operated lock 11 is of the keyless form and comprises the spring hasp member 20 which is hinged to the trunk cover and is adapted to swing into engagement with the escutcheon member 21 mounted on the body portion of the trunk. The hasp member is provided with an eyed projection 22 which extends into the trunk through an opening 23 formed in the escutcheon member and which is entered by a spring bolt 24 slidably mounted within a tubular portion 25 of the escutcheon member 21. The spring bolt 24 is provided with a guide stem 26 which passes through an opening 27 in the end wall of the tubular portion 25 and is limitedly, slidably connected to an actuating rod 28 slidably mounted on the inner side of one of the walls of the trunk by a chain or other flexible connection 29. The bar is slidably held by transversely extending holders 30 and extends to a position adjacent to the curved

lever arm 18 and the adjacent rod end is bifurcated as indicated by the numeral 31 in order to straddle said curved lever arm.

A light coiled spring 32 surrounds the bolt stem and is interposed between the bolt and the end wall of the tubular portion 25 and serves to yieldingly hold the bolt in locking position.

A heavy coiled spring 33 surrounding the actuating rod and having one of its ends resting against one of the holders and its opposite end 33' entering a notch or recess 34 formed in the rod 28 acts to normally hold the bolt 24 in unlocked position so that when the actuating rod is moved to compress this heavy spring the lighter or spring of less value of the bolt will yieldingly hold it in hasp engaging position.

The locking end of the bolt is beveled as indicated by the numeral 35 and the inner end 22' of the eyed projection 22 is likewise beveled to provide for the automatic engagement of the two parts when the hasp member is pushed into locked position.

When the keyed hasp member is pushed to closed position its lock barrel will engage the free end of the curved lever arm and swing it into the trunk and the curved portion of the lever arm which is engaged by the bifurcated rod end will engage said rod end and move the actuating rod to compress the heavy spring and permit the light spring to move the spring bolt to locking position so that when the keyless hasp member is pushed inwardly it will be engaged and locked by the bolt, and when the keyed hasp member is unlocked and swung outwardly by its spring the actuating rod will automatically open the keyless lock.

In the modified form shown in Figs. 6 and 7 the locking means is shown as mounted on a wardrobe trunk 36 which is divided medially, vertically into two sections 37 and 38 one of which is provided with a top cover 39.

The top cover 39 is hinged to the forward edge portion of the section 37 and swings over the open end of the section 38 and is locked thereto by an ordinary hasp lock 40 controlled, by a key 41. The two sections 37 and 38 are locked together by a keyless hasp lock 41 similar in every respect to the hasp lock 11 before mentioned and the different parts thereof will be indicated by the same reference characters.

The actuating rod 28' of this form extends upwardly to a position to be engaged by a projecting member 42 attached to the top cover so that when the top cover is raised the heavy coiled spring 33 will move the rod to release the spring bolt 24 from the hasp member 20 and when the top cover is closed the spring bolt will be in position to engage the hasp member.

While the trunk is shown as having but

two locks it is to be understood that any number of locks may be used and controlled from one keyed lock.

From the foregoing description it will be seen that the automatic locking means for trunks is of very simple construction and is well adapted for the purpose described.

What I claim as my invention is:

1. An automatic locking means, comprising a keyless hasp member; a bolt member positioned to engage the hasp member, means having a tendency for yieldingly holding the bolt member in locking position, an actuating rod having a movable connection with the bolt for moving the bolt only to open position, a coiled spring surrounding the rod and connected thereto and engaging a fixed part of the locking means for moving the rod only in one direction, said coiled spring being of greater strength than the yielding means of the bolt, a lever engaging the free end of the rod, and a keyed lock for automatically moving the lever.

2. An automatic locking means, comprising a keyless hasp member; a bolt member positioned to engage the hasp member, means having a tendency for yieldingly holding the bolt member in locking position, an actuating rod having a movable connection with the bolt for moving the bolt only in one direction, a coiled spring surrounding the rod and connected thereto and engaging a fixed part of the locking means for moving the rod in one direction, said coiled spring being of greater strength than the yielding means of the bolt, a curved lever engaging the free end of the rod for moving said rod in the other direction, and a keyed lock for automatically moving the lever.

3. An automatic locking means, comprising a keyless hasp member; a bolt member positioned to engage the hasp member, means having a tendency for yieldingly holding the bolt member in locking position, an actuating rod having a movable connection with the bolt, a coiled spring surrounding the rod and connected thereto and engaging a fixed part of the locking means for moving the rod in one direction, said coiled spring being of greater strength than the yielding means of the bolt, an escutcheon plate having an opening, a hasp member having a portion which enters the opening, and a lever pivoted to the escutcheon plate and engaging the rod and extending to a position in the path of movement of the hasp portion and being moved thereby and moving the rod in the other direction.

4. An automatic locking means, comprising a keyless hasp member, an escutcheon plate engaged thereby, a spring actuated bolt mounted on the plate and engaging the hasp member, a slidably actuating rod having one end portion positioned adjacent to

the bolt and provided with a transverse recessed portion, said adjacent rod end being flexibly connected to the bolt only to move the bolt when the rod is moved in one direction, a guide through which the rod slides, a coiled spring of greater strength than the spring of the bolt surrounding the rod and having one of its ends engaging the guide and its other end entering the transverse recess to move the rod in one direction, and means for moving the rod in the other direction.

5. An automatic locking means, comprising a keyless hasp member, an escutcheon plate engaged thereby, a spring actuated bolt mounted on the plate and engaging the hasp member, a slideable actuating rod having one end portion positioned adjacent to the bolt and provided with a 10 transverse recessed portion, said adjacent rod end being flexibly connected to the bolt to move the bolt only when the rod

is moved in one direction, a guide through which the rod slides, a coiled spring of greater strength than the spring of the bolt surrounding the rod and having one of its ends engaging the guide and its other end entering the transverse recess to move the rod in one direction, another escutcheon plate positioned adjacent to the free end of the rod and having an opening therein, a lever pivoted to the last mentioned escutcheon plate and engaging the free end of the rod to move the rod in the other direction, and a keyed hasp member 15 positioned to enter the last mentioned escutcheon plate and to engage and move the lever.

In testimony whereof, I affix my signature, in presence of two witnesses.

GEORGE HENRY WHEARY.
